UNITED STATES PATENT OFFICE.

JOHN U. WILER, OF MANSFIELD, OHIO.

FLUE-CLEANER.

SPECIFICATION forming part of Letters Patent No. 398,483, dated February 26, 1889.

Application filed May 4, 1888. Serial No. 272,788. (No model.)

To all whom it may concern:

Be it known that I, JOHN U. WILER, a citizen of the United States, residing at Mansfield, in the county of Richland and State of Ohio, have invented certain new and useful Improvements in Flue-Cleaners; and I do declare the following to be a full, clear, and exact description of the invention, such as will enable others skilled in the art to which it applies to make and use the same.

My invention relates to that class of flue-cleaners which uses steam for the purpose of cutting the tar or soot which accumulates on the inside of boiler-flues.

15 The object of my invention is to provide a flue-cleaner which is simple in construction and more efficient in operation.

With this object in view my invention consists in certain combinations of parts herein-20 after particularly described and claimed.

In order to make my invention more clearly understood I have shown in the accompanying drawings a means for carrying the same into effect.

25 In said drawings, Figure 1 is a plan view of a flue-cleaner embodying my invention. Fig. 2 is a longitudinal section of the same provided with an additional controlling spring.

Referring to the drawings, A indicates a 30 pipe adapted to conduct steam and provided at its forward end with a tapered and spring-controlled head, B, adapted to fit and close the end of a boiler-tube provided with a steam-jet opening or openings, S, and capable of 35 moving backward upon pipe A, when the stress of the spring is overcome, so as to open a valve or valves and place the interior of pipe A in communication with said opening S, with the result that a jet or jets of steam will be 40 delivered into and against the interior of the boiler-tube so closed.

I will now describe in detail the preferred construction by which the head B is so mounted, controlled, and operated.

45 C is a sleeve fitting closely and adapted to slide upon the forward end of pipe A. A stuffing-box, D, filled with any suitable packing, precludes the escape of steam rearwardly between the pipe and sleeve. A spring, F, mounted in the forward end of sleeve C and reacting against the end of pipe A, or a spring, F', bearing against the rear of stuffing-box D

and reacting against a collar, W, secured upon said pipe, or both of said springs, keep the said sleeve normally thrown forward. Its 55 movement in this direction is limited by the projecting flange of a cap, E, screwed into the forward end of pipe A. This cap at the same time closes the end of the pipe and makes it steam-tight and forms with the abutting shoulder of sleeve C a valve, U, which the action of the spring or springs already referred to tends to keep seated and closed. The forward portion of the sleeve forms a chamber, preferably a little larger in diameter than the outside of 60 pipe A, the front of which chamber is closed by a screw-cap, G, and the sides of which are provided with steam-escape openings L.

H indicates an opening or openings in the side of the forward end of pipe A, adapted, 70 when said pipe is moved forward relative to sleeve C, to deliver steam into said sleeve and to openings L. The head B is mounted upon said sleeve and moves therewith. It is preferably adjustable by means of a screw-thread, 75 R, and is secured in its adjusted position by a jam-nut, I. The sleeve C has an outwardly-projecting edge, c, and the head a correspondingly inwardly-projecting or forwardly-projecting edge or lip, b, and it is between these 80 edges that the opening S is formed in the shape of a narrow circumferential slit. This is preferably so beveled as to direct the sheet of steam forward and outward. Within head B is a chamber, V, into which apertures L 85 open.

The rear of pipe A is adapted to be coupled to a flexible hose, which will extend to any convenient steam-supply by means of a union, N, and coupling-sleeve M and a T-coupling, 90 J, while a suitable handle, P, of wood or hollow metal, is connected with pipe A by a reducer, K, closed at its front end and by said T.

The operation of the cleaner is as follows: 95 A flexible hose from a steam-boiler is connected with union N. The operator then, by means of the handle P, lifts the device and inserts the forward end of it into the tube to be cleaned, so that the opening S will be encircled by the tube while the edge of the latter bears against the conical or rounded periphery of the head B. The operator now presses forward on the handle with the result that pipe A overcomes the stress of the spring

or springs and moves forward in the sleeve C. Valve U is thus unseated and openings H brought into position to deliver a volume of steam under pressure to openings L and 5 chamber V. From the latter it escapes into the boiler-tube through opening or slit S impinging forcibly upon the interior surface of the tube or flue to be cleaned and clearing it of all accumulations and obstructions. When 10 the cleaning of a flue is completed, the pressure upon the handle P is relaxed, the valve U is closed by the operation of the spring, and the device may be removed to and inserted in another flue, and the above-described 15 operation repeated.

Having thus described my invention, what I claim, and desire to secure by Letters Patent of the United States, is—

1. In a steam flue-cleaner, the combination, 20 with the steam-supply pipe, of a spring-controlled sleeve adapted to slide thereon and having an outwardly-projecting edge, and a tapered head, B, shaped to co-operate with said projecting edge to produce a narrow 25 steam-jet opening and longitudinally-adjustable upon said sleeve to regulate the size of said opening, substantially as set forth.

2. The combination, with the steam-supply pipe, of a sleeve fitted to slide thereon and 30 having a tapered head, B, said sleeve having a chamber in its forward end, and a spring,

F, situated in said chamber and bearing against the end of said pipe for forcing the sleeve forward relative to said pipe, substantially as set forth.

3. The combination, with a steam-supply pipe, of a sleeve fitted to slide longitudinally thereon and having a tapered head, and a steam-jet opening formed between relatively adjustable parts, a spring for forcing said 40 sleeve forward, and a valve and valve-seat independent of the jet-opening on said pipe and sleeve, which valve is closed by the action of the spring, and when closed prevents further movement of the sleeve relative to the pipe, 45 substantially as set forth.

4. The combination, with a steam-supply pipe, of a sleeve fitted to slide thereon, a spring for forcing said sleeve forward upon the pipe, an outwardly-projecting flange or edge upon 50 the sleeve, and a tapered head shaped to co-operate with said edge to form a narrow steam-jet opening and adjustably mounted upon a screw-thread upon said sleeve, substantially as set forth.

In testimony whereof I affix my signature in the presence of two witnesses.

JOHN U. WILER.
